(57) **CLAIM**

The ornamental design for a heat press transfer printing machine assembly, as shown and described.

DESCRIPTION

FIG. 1 is a front elevation view of the heat press transfer printing machine assembly;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and

FIG. 7 is a perspective view showing the heat press transfer printing machine;

FIG. 8 is a front elevation view of the main body of the heat press transfer printing machine assembly, shown separate in order to show aspects of the design not otherwise apparent;

FIG. 9 is a rear elevation view thereof;

FIG. 10 is a left side elevation view thereof;

FIG. 11 is a right side elevation view thereof;

FIG. 12 is a top plan view thereof;

FIG. 13 is a bottom plan view thereof; and

FIG. 14 is a front elevation view of the pedestal of the heat press transfer printing machine assembly, shown separate in order to show aspects of the design not otherwise apparent;

FIG. 15 is a rear elevation view thereof;

FIG. 16 is a left side elevation view thereof;

FIG. 17 is a right side elevation view thereof;

FIG. 18 is a top plan view thereof;

FIG. 19 is a bottom plan view thereof; and,
